UNITED STATES PATENT OFFICE.

JOHN O. NEIKIRK, OF LOMBARD, ILLINOIS, ASSIGNOR TO RODGER BALLAST CAR CO., OF CHICAGO, ILLINOIS, A CORPORATION OF MAINE.

CONVERTIBLE-CAR CONSTRUCTION.

1,397,695.

Specification of Letters Patent.

Patented Nov. 22, 1921.

Application filed August 9, 1919. Serial No. 316,311.

To all whom it may concern:

Be it known that I, JOHN O. NEIKIRK, a citizen of the United States, residing at Lombard, in the county of Du Page and State of Illinois, have invented certain new and useful Improvements in Convertible-Car Constructions, of which the following is a specification.

This invention relates to convertible car constructions.

The general object of the invention is to provide a car of the Hart convertible type from which the load may be dumped to the side or to the center, or partially to the side and partially to the center.

This object is attained by providing a car having a central longitudinal stationary hopper portion, the car being provided along the sides of the floor with swinging doors mounted so that they may drop downwardly to a dumping position, be raised to a horizontal position to form a part of the flat floor of the car, or swung upwardly to an inclined position, in which case the doors form an extended wall of the central hopper.

In this particular aspect, therefore, the invention comprises a car having the stationary central longitudinal hopper portion with the swinging doors mounted along the upper outer edges of the hopper portion, which doors in one position form extensions of the hopper sides. In this embodiment of the invention, the hopper sides are completed by freely swinging doors which in one position form portions of the car sides.

The invention is illustrated on the accompanying sheets of drawings in which,—

Figure 1 is a transverse sectional view of a convertible car embodying my invention; 40 and

Fig. 2 is a longitudinal sectional view of the same car.

Referring to the drawings, it will be noted that I have shown a convertible car having sides including stakes 10, which are connected at their lower ends by continuous cross beams 11, whereby the load of the car is transmitted to the sides thereof. Longitudinal sills 12 are mounted over and rest upon the cross beams 11. The body of the car includes a central stationary longitudinal hopper 13 formed by an inclined stationary wall 14 and an inclined movable wall in the form of a door 15, whereby the load may be center-dumped.

When the car is used as a flat bottom car, the central hopper 13 is covered. In this particular case, it is covered partially by members 16 which, when the car is arranged as a hopper car, are used as hopper end walls 60 spaced from the regular car end walls 17, as shown in dotted lines in Fig. 2. The remaining portion of the hopper 13 at each end is covered by a movably mounted member 24, which when the car is used as a hopper car is moved over upon the floor end portion 25 as shown in dotted lines in Fig. 2. The flat floor adjacent the central hopper 13 is formed by longitudinally extending doors 18, which are pivotally mounted at 19 65 along their inner edges or along the upper outer edges of that portion of the hopper 13 below the floor level.

As shown at the left hand side of the Fig. 1, the floor door 18 is arranged in a horizontal plane, in which position it is located when the car is used as a flat bottom car. Under the same circumstances, the side wall doors 20 are in a vertical position engaging the side stakes 10, the car sides also including stationary portions 21 located above the doors 20. It will be noted that the doors 20 in their vertical positions form stops, which prevent the floor doors 18 from being moved upwardly from a horizontal position. 70 When the doors 20 are swung inwardly from their vertical position as shown at the right hand side of Fig. 1, the floor doors 18 may be raised.

When the car is arranged as a flat bottom 90 car, the load may be dumped to the sides thereof by dropping the doors 18, said doors being provided with suitable operating mechanism, including chains or cables 22 and operating shafts 23 carried by the side 95 of the car.

When it is desired to change the car from a flat bottom car to a central hopper car, the same is done by shifting the car side doors 20 into an inclined position, as shown at the 100 right hand side of the Fig. 1, and in which position the side wall doors 20 are supported by the floor doors 18, which also are moved into an inclined position, the floor doors 18 being supported in the inclined position by the door operating mechanism, including the cables 22 and shafts 23. It will be noted that the floor doors 18 at their outer ends are provided with laterally extending strut portions 26 to which the cables 110

are connected. The effect of this strut connection is to force the door 18 inwardly toward the center of the car when it is raised thereby forming an effective support for the 5 side doors 20.

When the car is arranged as a center hopper car, the sides of the lower hopper portion 13 and the floor and side wall doors 18 and 20 respectively lie in the same inclined planes. It will be understood also 10 that the temporary hopper floor portions 16 and 24 will be moved from their full line positions as shown in Fig. 2 to their dotted line positions as shown in the same figure. 15 Heretofore with the central hopper arrangement, no provision has been made to dump a portion of the load to the sides of the car. However, by means of my improved door arrangement, the doors 18 may 20 be lowered from their inclined position, in which they form hopper side walls, to positions wherein a portion of the load will be dumped to the sides of the car. It will be understood that as the floor doors 18 are 25 moved downwardly from an inclined position, the side wall doors 20 will swing laterally to their vertical positions, thereby permitting an increased flow of material past the floor doors 18 after the latter have 30 passed downwardly beyond a horizontal position. If desired, the central hopper door 15 may be opened at the same time for center-dumping.

It is my intention to cover all modifications 35 of the invention falling within the spirit and scope of the appended claims.

I claim:

1. A car of the class described, including a central longitudinally disposed hopper portion, doors hinged along the upper outer edges of said hopper portion arranged to 40 form in one position a part of the horizontal floor of the car and to be swung upwardly from the horizontal position to 45 form a portion of a hopper side and swung downwardly for dumping purposes, and freely swinging side wall doors which in an inclined position also form a portion of a hopper side, said side wall doors when in a 50 vertical position forming stops for said floor doors preventing movement of the latter in a given direction.

2. A car of the class described, including a body having a side wall door and a floor door 55 which may be moved into an inclined position to form a hopper side wall, the side wall door in one position acting as a stop to prevent upward swinging of the floor door from a horizontal position, the floor door being

movable from said inclined position for side 60 dumping.

3. A car of the class described, including a body having a side wall door and a floor door which may be moved into an inclined position to form a hopper side wall, the side 65 wall door being supported by the floor door in said inclined position, and the floor door being movable from said inclined position for side dumping.

4. A car of the class described, including a body having a side wall door and a floor door which may be moved into an inclined position to form a hopper side wall, one of said doors being supported by the other in said position, the floor door being movable from 75 said inclined position for side dumping, and said side wall door moving laterally as the floor door moves downwardly for increasing the flow of the dumpable material.

5. A car of the class described, including a body having movable side portions and movable floor portions which respectively occupy vertical and horizontal positions when the car is arranged as a flat bottom car and which take an inclined position to form a 85 hopper side wall when the car is arranged as a hopper car, the movable side portion being supported by the movable floor portion in said inclined position, said floor portion being movable for side dumping from an inclined hopper position and from a horizontal 90 position.

6. A car of the class described, including a body having a movable side wall door and a movable floor door which when the car is 95 arranged as a flat car are respectively in vertical and horizontal positions, said doors being movable into an inclined position to form a hopper side wall, said floor door being movable from its inclined and horizontal 100 positions for side dumping, and a door operating mechanism for said floor door whereby the latter is supported in its inclined position and in turn supports the side wall door in inclined position.

7. A car of the class described, including a body having a side wall door and a floor door which may be moved into an inclined position to form a hopper side wall, and means connected to the floor door including a laterally extending strut portion and an associated flexible member whereby the floor door will support the side wall door when both are in an inclined position.

Signed at Lombard, Illinois, this 31st day 115 of July, 1919.

JOHN O. NEIKIRK.
